CARTRIDGE

Louis A. Macklanburg, Oklahoma City, Okla.

Application April 29, 1935, Serial No. 18,722

5 Claims. (Cl. 206—56)

My invention relates to the method of and apparatus for loading guns or other apparatus used for dispensing caulking materials, putty, grease or other liquid or semi-liquid.

At the present time it is common practice to apply caulking material and the like from a gun usually consisting substantially of a cylindrical barrel having a plunger therein for forcing the material outwardly through a suitable nozzle. The gun is loaded by suction created at the nozzle by drawing the plunger away from the nozzle end of the cylinder. The substance usually used in guns of this type are somewhat viscous and in order to load the gun not only is considerable effort required, but before the gun can be used after being loaded it must be wiped. A waste of the caulking material is not only thus occasioned, but considerable inconvenience is caused.

The prime object of the present invention is to provide for insertion in the gun a cartridge or load of the material to be dispensed, and means for removing the envelope of the load and leaving the material in the gun.

In my co-pending United States patent application filed December 29, 1934, under Serial No. 759,726, and entitled Apparatus for and method of loading guns for dispensing viscous or semi-liquid materials, I have disclosed a cartridge for similar materials which is adapted to be placed in the gun, and the walls of which collapse in the gun as the container is emptied by pressure of the gun's plunger. That application discloses that it is preferred to form the cartridge of "Cellophane".

It has been found that many caulking guns now in use are so constructed that as the walls of the cartridge are collapsed the pressure forces the "Cellophane" between the plunger and the inner surface of the gun barrel. This requires the gun to be disassembled in order to remove the envelope of the cartridge. My present invention is so designed that the walls of the cartridge may be removed leaving only the commodity to be dispensed within the gun.

Other objects of the invention are to provide an apparatus of this class which is new, novel, practical and of utility; which will load the gun without any mess or discomfort to the operator; which will prevent loss of material; which is speedy in operation; which is cheap to manufacture; and, which will be efficient in accomplishing all the purposes for which it is intended.

With these and other objects in view as will more fully appear hereinbelow, my invention consists in the construction, novel features, and

combination of parts hereinafter more fully described, pointed out in the claims hereto appended, and illustrated in the accompanying three-sheet drawings, of which,

Figure 1 is a fragmentary perspective view of the exhaust end of the barrel of a usual caulking gun, and showing one embodiment of the invention operatively installed therein;

Figure 2 is a fragmentary sectional view of the embodiment illustrated in Fig. 1;

Figure 3 is a view similar to Fig. 1 showing a slightly different embodiment of the invention;

Figure 4 is a perspective view of the cartridge installed within a fragment of a usual gun barrel and showing another embodiment;

Figures 5, 6 and 7 are fragmentary elevational views partially in section showing three other embodiments of the invention;

Figure 8 is a perspective view of a closure used in connection with the embodiments of the invention illustrated in Figs. 7 and 9;

Figure 9 is a fragmentary perspective view of the rear portion of a usual caulking gun showing a still different embodiment;

Figures 10, 11, 12 and 13 are top views of four different plates which may be used in connection with the embodiments illustrated in Figs. 1, 2 and 3; and,

Figure 14 is a pictorial view showing a usual caulking gun being loaded by the method disclosed herein.

Like characters of reference designate like parts in all the figures.

It is understood that various changes in the form, proportion, size, shape, weight and other details of construction, within the scope of my invention may be resorted to without departing from the spirit or broad principle of my invention and without sacrificing any of the advantages thereof; and it is also understood that the drawings are to be interpreted as being illustrative and not restrictive.

The inventive idea involved is capable of receiving a variety of mechanical expressions one of which, for the purpose of illustrating the invention, is shown in Figs. 1 and 2 of the accompanying drawings wherein:—

The reference numeral 1 indicates the barrel of a usual caulking gun having an annular flange 2 surrounding its open end from which the usual nozzle and nozzle cap has been removed. This embodiment of the invention includes a cylindrical cartridge 3 adapted to be inserted in the barrel 1 and preferably consisting of an envelope of suitable flexible material such as "Cellophane" which

contains the commodity 4 with which it is desired to load the gun barrel. The cartridge 3 is formed at one end with a twisted portion 5 (Fig. 4) and at its other end is provided with a surplus of "Cellophane" which is formed into a neck 6. A perforated disc 7 is inserted over the neck 6 and a handle 8 is also installed upon the neck. A knot 9 acts to hold the disc 7 and the handle 8 upon the neck 6. Preferably, the disc 7 is provided with a rounded annular upstanding flange 10 surrounding its perforation to prevent tearing the envelope of the cartridge as it is drawn through the perforation. The flange 10, however, does not in any manner act as a nozzle for the commodity 4 because the disc 7 must necessarily be removed from the barrel 1 before the usual barrel-cap and nozzle can be installed.

In loading a gun with this embodiment the operator holds the disc 7 against the flange 2 of the barrel 1 with two fingers of one hand and grasps the handle 8 with his other hand. He then pulls upon the handle and draws the "Cellophane" envelope or container outwardly through the perforation in the disc 7, causing the material 4 to untwist the twisted portion 5 at the other end of the container and open the same. The material 4 is thereby forced from the container and remains within the barrel.

In Fig. 3 is illustrated an embodiment in which the handle 8 and knot 9 are supplanted by a loop 11 which is adapted to receive one of the operator's fingers whereby the "Cellophane" container may be withdrawn through the disc 7. The loop 11 may be formed in any desired manner such as by a binding cord 12 or the loop may be formed by tying the free end of the neck 6 upon itself.

If it is found desirable in order to safely ship and handle the cartridges to make the twisted portion 5 of considerable length, it will probably be necessary for the operator to sever the twisted portion 5 close to the end 13 (Fig. 4) of the cartridge before placing the load in the gun.

In Fig. 4 is illustrated an embodiment in which the disc 7 has two oppositely disposed latch members, one of which is indicated by the reference numeral 14. Each latch member has a return portion 15 for fitting beneath the flange 2 and holding the disc in contact with the barrel. The flange 2 of the barrel has oppositely disposed notches, one of which is indicated by the reference numeral 16, for permitting the passage of the latch return 15 past the flange. In installing the disc of this embodiment upon the barrel, the disc is slightly rotated after the latch returns 15 have been passed through the notches 16.

Providing the flange 2 of the barrel 1 with the notches 16 is not a part of this invention since the notches are common to caulking and grease guns for the purpose of receiving projections upon the usual nozzle cap.

In Fig. 10 is illustrated a disc 7 having an elongated slot 17 for passing over the neck 6 of the cartridge instead of the round perforation illustrated in Figs. 1 and 2.

It may be found desirable to use in lieu of the disc 7 an elongated plate 18 having either an elongated slot 17 or a circular perforation, not shown, for receiving the neck 6. In Fig. 12 the plate 18 is bifurcated at one end by a slot 19 which may be carried by the operator and inserted over the neck 6 to act in lieu of the disc 7 or the plate 18. In Fig. 13 the plate 18 is not only bifurcated by the slot 19 but is also provided with a circular enlargement 20 in communication with the inner end of the slot. In this embodiment the neck 6

is passed through the slot 19 into the enlargement 20 before the "Cellophane" container is withdrawn.

It will be obvious that the plates illustrated in Figs. 11, 12 and 13 and the discs illustrated in Figs. 1, 2, 3, 4 and 10 may be used with either the handles 8 or the loop 11 as desired. Also, that any desired opening to retain within the gun barrel the material to be dispensed and which will also permit withdrawal of the "Cellophane" container, 10 can be utilized.

Attempt has heretofore been made to utilize the usual nozzle cap 21 of the gun (Fig. 5) as a means for retaining the commodity in the gun as the envelope is withdrawn through its usual outlet. It 15 has been found, however, that the usual outlet in the nozzle cap is too large to be practical for this use and consequently some of the commodity is permitted to be withdrawn from the gun with the envelope.

It has also been found that after the gun has once been used, the nozzle is left full of the commodity being dispensed. Consequently with some commodities it is impossible and with all commodities it is impractical to force the neck 6 of a second container through the filled nozzle even though only a straight neck were provided upon the container. If this were done the operator would be forced to grasp the neck, which would then be smeared with the content, in order to withdraw the wrapper. In Fig. 7 the nozzle cap 21 is shown as having a centrally perforated outstanding exteriorly threaded boss 22 through which the neck 6 may be inserted. The perforation in the boss 22 acts in the same manner as does the perforation in the discs or the plates. In Fig. 9 is illustrated the rear or operating end of a usual caulking or grease gun. In this embodiment the gun's plunger 23 is illustrated in dotted lines at the rearmost end of its throw. The barrel 1 is provided with a centrally perforated exteriorly threaded outstanding boss 24 which lies slightly ahead of the plunger when in its rearmost position and through which the neck 6 of the cartridge 3 may be passed. The boss 24 acts similarly to the boss 22.

In the embodiments illustrated in Figs. 7 and 9 after the "Cellophane" container has been withdrawn a threaded cap 25 (Fig. 8) will be utilized upon either the boss 22 or the boss 24 to close its perforation.

In Fig. 6 is illustrated an embodiment whereby rollers are used for compressing the neck 6 of the container 3 and permitting its withdrawal while retaining the material to be dispensed within the barrel 1 of the gun. In this embodiment oppositely disposed arms 25 and 26 are pivotally mounted upon outstanding elements 27 and 28 respectively and the free ends of the arms each carry a roller 29. The arms may be swung upwardly into the position illustrated for engaging the neck 6, but normally hang or are held by any suitable means away from the exhaust end of the barrel.

From the foregoing description it is thought that the operation of the various embodiments disclosed will be obvious to one versed in the art and that further description thereof is unnecessary. Suffice to say, that the discs 7 illustrated in Figs. 1, 2, 3, 4 and 7, and the plate 18 shown in Fig. 11 can be produced at a cost which will permit their being installed upon each cartridge and then being cast aside after use.

Obviously, the invention is susceptible of embodiment in forms other than that which is illus-

trated in the accompanying drawings and described herein, and applicable for uses and purposes other than as detailed, and I therefore consider as my own all such modifications and adaptations and other uses of the form of the device herein described as fairly fall within the scope of my invention.

Having thus described my invention, what is claimed and desired to be secured by Letters 10 Patent, is:

1. A cartridge for filling rigid containers with a pliant commodity, comprising a flexible envelope with the commodity therein, a portion of said envelope extending beyond the commodity 15 and collapsed to form a neck, and a rigid perforated element surrounding and carried by the neck, the perforation in said element being sufficiently small to retain substantially all of the commodity within the container when the filled 20 envelope is placed in the container and is then drawn therefrom through the element.

2. Organization as described in claim 1, in which the free end of the neck is provided with 25 a hand hold means.

3. Organization as described in claim 1, in which the perforated element includes a disc having a passage through which the neck extends, and means carried by the disc for remov-

ably connecting it to the open end of the container.

4. A cartridge for filling rigid containers with a pliant commodity, comprising a flexible envelope with the commodity therein and adapted to fit 5 within the container to be filled, a portion of said envelope extending beyond the commodity and collapsed to form a neck, and a plate separate from the container and having an opening through which the neck may be passed, said 10 opening being sufficiently minute to reduce the body of the envelope and exude the commodity therefrom into the container when the cartridge is then drawn out of the container and through 15 the plate.

5. A cartridge for pliant commodities comprising, a flexible envelope containing the commodity and having one openable end, the other end portion of said envelope extending past the 20 commodity and being collapsed to form a neck, a rigid element having an opening for receiving the neck, said opening being sufficiently small to collapse the body of the envelope and prevent the passage of any appreciable amount of the 25 commodity therethrough when the envelope is drawn through the element.
